UNITED STATES PATENT OFFICE.

DANIEL SULLIVAN, OF CENTRAL FALLS, RHODE ISLAND.

FRONT FOR STEAM-BOILERS.

SPECIFICATION forming part of Letters Patent No. 247,226, dated September 20, 1881.

Application filed February 5, 1881. (No model.)

To all whom it may concern:

Be it known that I, DANIEL SULLIVAN, of Central Falls, in the county of Providence and State of Rhode Island, have invented certain new and useful Improvements in Fronts for Steam Boilers or Generators; and I do hereby declare that the following is a full, clear, and exact description of the invention, that will enable others skilled in the art to which it applies to make and use the same, reference being had to the accompanying drawings, forming a part of this specification, in which—

Figure 1 shows a front elevation, Fig. 2 a section, of my boiler-front.

15 Same letters show like parts.

My invention aims at producing a front for steam boilers or generators which shall be lighter, cheaper, and more durable than those now in use.

20 My device will be readily understood by reference to the accompanying drawings.

At a is shown the front, constructed of wrought-iron or steel, and provided with the usual doors and other openings, b b b. Around the edge is bolted a molding or angle-iron, c, entering the brick-work, as shown in the section, and

assisting to hold the front in position, and at the same time to exclude the cold air from the boiler. At d is a T-iron bolted across the boiler-front, serving to stiffen it, while an angle-iron, 30 e, serves the same purpose, and also as a support for the chute f.

My front can be made of comparatively thin iron, while retaining equal or greater strength than the ordinary cast-iron front now in use, 35 nor is it liable to crack or break from unequal expansion or contraction.

What I claim as my invention is—

The improved boiler-front herein described, made of wrought-iron or steel, and provided 40 with the molding or angle-iron c, extending entirely around its edge and entering the brick-work, said front being attached and braced at d e, substantially as herein set forth and shown.

In testimony that I claim the foregoing I 45 have hereunto set my hand this 29th day of January, 1881.

DANIEL SULLIVAN.
